UNITED STATES PATENT OFFICE.

CHARLES A. SCHROYER, OF CHICAGO, ILLINOIS.

DRAW-BAR FOR RAILWAY-CARS.

SPECIFICATION forming part of Letters Patent No. 599,637, dated February 22, 1898.

Application filed March 22, 1897. Serial No. 628,572. (No model.)

To all whom it may concern:

Be it known that I, CHARLES A. SCHROYER, a citizen of the United States, residing at Chicago, in the county of Cook and State of Illinois, have invented certain new and useful Improvements in Draw-Bars for Railway-Cars, of which the following is a specification.

The object of my invention is to provide a simple, economical, and efficient draw-bar 10 with buffering mechanism and inclosing holding-stop mechanisms, and is intended to be an improvement upon the mechanism described and claimed in Letters Patent No. 438,386, granted to me the 14th day of October, 1890.

15 The invention consists in the features, combinations, and details of construction hereinafter described and claimed.

In the accompanying drawings, Figure 1 is a plan view of a draw-bar, looking at it from 20 below and constructed in accordance with my improvements; Fig. 2, a side elevation of the rear end of the draft-arm and a portion of the stop-casting; Figs. 3 and 4, enlarged cross-sectional views taken on the lines 3 and 4, respectively, of Fig. 1; Fig. 5, a side elevation of one of the inclosing stop-castings, looking at it from the interior; Fig. 6, a plan view of 25 a modified form of draw-bar and other parts constructed in accordance with my improvements, looking at it from below; Fig. 7, a side elevation of one of the inclosing stop-castings shown in Fig. 6, looking at it from the interior; and Fig. 8, a cross-sectional view taken on line 8 of Fig. 6.

30 In constructing a draw-bar in accordance with my improvements I make a draw-bar proper, A, of the desired size and shape and provide it with a yoke B, which forms a pocket, in which the main buffer-spring C is inserted.

35 Arranged in the same pocket are follower-plates c c', one at each end of the main spring mechanism, so that when the parts are in their operative position the follower-plate c, by means of the yoke, is pulled against the

40 main spring, and when the draw-bar is pushed backward it impinges directly on the spring by means of the follower-plate c'. To sustain these parts in position and provide stops for limiting the motion of the follower-plates

45 and compressibility of the buffer-springs, I provide stop-castings D D', one at each side of the draft-arm and "gained" or otherwise

set into the sills E E' and provide them with shoulders d d' to limit the motion of the follower-plates. The stop-castings are preferably secured to the sills by means of bolts and nuts e, which sustain them in desired position, and such castings may be provided with bars d'', that are secured to the lower side of the castings and prevent the follower-plates from 55 being removed until desirable or necessary.

50 In this art and in my former construction springs for absorbing the shocks due to the usage of the railway-cars are arranged in tandem relation. These springs are bolted 60 together and are held in proper relation and connection with the draw-bar by means of a long bolt. This construction involves considerable labor and time in the assembling 65 of the parts, for the reason that the draw-bar with all of the springs has to be assembled first and then raised into position. Being very heavy and cumbersome it takes considerable time and involves considerable trouble to place such parts in their proper position. In 70 order to obviate this objection and enable the parts to be placed in position separately and economically, I provide the stop-castings D D' with a rearward extension D² and D³, which form a cylindrical chamber or pocket d'', into 75 which the rear or auxiliary spring mechanism G may be inserted. This auxiliary spring is usually a little longer than the main springs, so that the compressibility or movement of the main spring may be exhausted before the 80 second spring is exhausted or its motion completed. The principal advantage due to the inclosing stop-casting above described is the fact that the auxiliary spring may be independently inserted in position first and the 85 draw-bar with its pocket and follower-plates be afterward inserted in place. It will be apparent that this may be performed quickly and economically.

90 In Figs. 6, 7, and 8 I have shown my improvements applied to a draw-bar in which a set of springs H and H' are used in multiple relation with each other—that is, two springs or sets of springs are used side by side. The draw-bar A with its yoke B is in all respects 95 constructed similar to those described in connection with the preceding figures. The inclosing stop-castings I and I' differ only in 100 size and shape and are provided with stops

i i' to limit the movement of the follower-plates and with rearward extensions I^2 and I^3 , which form a rear inclosing pocket i^3 for the auxiliary spring J . The assembling of 5 the parts and the operation of the draw-bars and attached mechanisms are in all respects the same as that described in connection with Figs. 1 and 2.

I claim—

- 10 In a draw-bar mechanism, the combination of a draw-bar provided with a main spring-pocket, main spring mechanism in such pocket, follower-plates arranged one at each

end of the main spring mechanism, stop-castings arranged one at each side of the draw-bar 15 to limit the movements of the follower-plates and provided with rearward extensions to form a holding-pocket and substantially a complete closure for auxiliary spring mechanism, and auxiliary spring mechanism in 20 the pocket of the stop-casting, substantially as described.

CHARLES A. SCHROYER.
